WATER-COOLED LINTEL AND SKEWBACK
CHANNEL COOLER

Harry F. Nulph, East Liverpool, Ohio

Application December 30, 1949, Serial No. 136,086

2 Claims. (Cl. 122—499)

1

This invention relates to new and useful improvements in water-cooled door frames of the type used in the furnaces of the steel industry, and more particularly pertains to a water-cooled lintel having improved circulation means and means for attaching the same to a supporting structure.

The primary object of this invention is to provide support for the masonry above furnace openings, which will permit efficacious replacement of bricks or the like adjacent the opening that have been destroyed by excessively high temperatures.

Another important object of this invention is to provide such a support which will not be subject to excessive thermal expansion so as to avoid damage to or weakening of the furnace masonry.

Another important object of this invention is to provide a support of this character, which may be easily installed or removed and which may be supported upon conventional buck stays.

Another important object of this invention is to provide a support of this character capable of realizing the foregoing objects, which may be secured to buck stays in such a manner as to avoid any considerable heat exchange therewith, while obtaining adequate support therefrom.

Still another important object of the invention is to provide a device of this character which is liquid cooled and in which the liquid circulation is such as to insure adequate cooling to the support at the points where the same is more subject to deleterious effects of heat.

A meritorious feature of the present invention resides in the sleeves, which receive the fastening bolts by which the lintel is supported upon the buck stays, extending through the rear portions of the hollow jacket, whereby the sleeves and the bolts are water-cooled and the arrangement of the portions being such with respect to the buck stays that heat insulating pads, such as asbestos, can be inserted therebetween.

Another important feature of the present invention resides in the contour of the front wall of the lintel, whereby access is permitted to the water inlet pipes, adequate support given the furnace roof, radiant energy reflected from the same, and the combustion products slide off the same.

Another important feature of the present invention resides in the laterally extending portions being slightly higher than the body section to accommodate steam if such is formed, and to permit access to bricks overlying the body section.

A final important feature to be specifically enumerated herein resides in the water circula-

2

tion afforded by the lintel, whereby cold water is directed to the danger points, and the flow of the water being forced to the rear of the laterally extending portions, while steam if such is formed is directed away from the forward sloping wall and immediately out of the outlet pipes, thereby avoiding high temperatures in the lintel by not permitting the formation of superheated steam at any point in the lintel.

10 These, together with various ancillary features and objects of the invention which will later become apparent as the following description proceeds, are attained by the present invention, a preferred embodiment of which has been illustrated by way of example only in the accompanying drawings, wherein:

Figure 1 is a front elevational view of the lintel, showing the same in position on a furnace and secured to buck stays by bolts, indicated in dotted outline;

Figure 2 is a rear elevational view of the lintel, showing the same in use on a furnace;

Figure 3 is a vertical transverse sectional view of the present invention, being taken substantially upon the plane of the section line 3—3 of Figure 1;

Figure 4 is a top plan view of the lintel, the attaching sleeves being shown in dotted outlines;

Figure 5 is a horizontal sectional view of the lintel, being taken upon the plane of the section line 5—5 of Figure 6;

Figure 6 is a vertical transverse sectional view of the lintel, being taken upon the plane of the section line 6—6 of Figure 4;

Figure 7 is a vertical longitudinal sectional view of the lintel, being taken substantially upon the plane of the broken section line 7—7 of Figure 6; and

Figure 8 is another vertical transverse sectional view of the lintel, this view being taken upon the plane of the section line 8—8 of Figure 4.

Reference is now made more specifically to the accompanying drawings, wherein like numerals designate similar parts throughout the various views, and in which the lintel is indicated generally by the numeral 10.

The lintel 10 comprises a substantially U-shaped hollow jacket having a body section 12 and rearwardly extending portions 14 at the opposite extremities of the body section 12. The end walls 16 of the body section 12 extend rearwardly to define the outer side walls 18 of the portions 14; while the inner walls 20 of the portions 14 terminate at the opposite extremities of the rear wall 22 of the body section 12; so that

the interiors 24 of the portions 14 are in free communication with the interior 26 of the body section 12, as will be readily understood upon reference to Figure 5.

As best shown in Figures 1 and 7, the upper wall 28 of the body section 12 is downwardly curved at 30 adjacent its opposite ends 34 to be lower than the upper walls 36 of the portions 14 substantially its entire length for a purpose to become subsequently apparent.

The rear wall of the body section 12 includes an upper vertical portion 38 and horizontal portion 40 extending rearwardly from the lower edge of the portion 38. A wall portion 42 extends rearwardly and downwardly from the outer edge of the portion 40 and terminates at the bottom wall 44 of the lintel 10, the rear wall being so contoured for a purpose presently clear.

A plurality of longitudinally spaced water inlet pipes extend vertically through the portion 40, and have their lower ends terminating in spaced relationship above the bottom wall 44 of the lintel 10, and the upper ends of the water pipes 46 are threaded as at 48 for connection to a source of water, not shown, for forcing water into the body section 12 immediately above the bottom wall 44 thereof. Pairs of spaced hot water outlet pipes 50 extend upwardly from each of the portions 14, the lower ends of which communicate with the upper parts of the interiors 24, and the upper ends of which are threaded as at 52 for connection to a water cooling system or the like, not shown, so that the water can be recirculated to the pipes 46 if desired. Outlet pipes 54 are connected to the lower rear extremities of the portions 14, and each of the pipes 54 is provided with valves 56 for controlling the discharge therefrom. The pipes 54 and valves 56 are for the purpose of permitting the lintel 10 to be drained or flushed free of sediment which may have been deposited therein.

Vertically spaced sleeves 58 extend through each of the portions 14, and are in sealed engagement with the walls 18 and 20, as by welding 60, the arrangement being such that water circulating in the interiors 24 circulates about the sleeves 58 so as to cool the exterior thereof.

As shown clearly in Figures 1, 2 and 3, the lintel 10 is disposed above an opening 62 in the side wall 64 of a furnace 66 that is constructed of masonry, such as fire brick, or other refractory material as desired, and which includes an arched roof construction 68 and upright buck stays 70 disposed on opposite sides of the opening 62. The lintel 10 is supported by the buck stays 70 by means of bolts 72 which extend through suitable apertures in the buck stays 70 and the sleeves 58, the arrangement being such that asbestos pads or the like, not shown, may be disposed between the portions 14 and the buck stays 70 if desired.

With particular reference to Figure 3, it will be seen that the rear wall of the lintel 10 provides adequate support for the roof construction 68, while the horizontal portion 40 and the upper wall 28 being depressed permit access to the inlet pipes 46 and the bricks forming the roof structure 68.

It will be readily appreciated that the portions 14 may, if desired, be formed to extend below the body section 12 to define cooled side walls for the opening 62, and with the same being secured to the buck stays in a similar manner throughout their vertical extent without departing from the spirit of the instant invention.

The circulation of water through the lintel 10 will be readily understood. Water admitted to the interior of the body section 12 intermediate its ends proceeds from immediately above the bottom wall 44 thereof, to the portions 14 to insure cooling of the body section 12 throughout its entire length and upwardly to the outlet pipes 50 so as to cool the sleeves 58. It will be noted that any steam formed against the sloping wall 42 is directed upwardly and away from the wall 42 to provide for good heat exchange between the liquid water in the body section 12 and the wall 42, while such steam thus formed proceeds immediately to the upper portion of the interiors of the portions 14 so as to be immediately removed from the lintel 10 through the pipes 50. It will also be noted that the sloping wall 42 does not permit the accumulation of combustion products upon the lintel 10 and that the sloping of the same tends to reflect radiant energy emanating from the combustion chamber of the furnace away from the lintel 10.

The lintel 10 is preferably constructed of steel plate to insure sufficient strength in the same for supporting the roof structure, and it will be seen that the form of the same is such that the same may be readily fabricated by suitable welding.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A lintel for furnace structures, said lintel comprising a hollow substantially U-shaped member including a body section and a pair of spaced parallel leg portions joined by said body section, said leg portions each having flat upper and lower horizontal walls and inner and outer vertical side walls, said body section also including flat upper and lower walls, said lower wall of said body section being coplanar with said lower walls of said leg portions and said upper wall of said body section being in a horizontal plane below a horizontal plane of the upper walls of said leg portions, said body section including a stepped rear wall having a vertically disposed upper portion, a vertically inclined rearwardly and downwardly sloping lower portion and a horizontal portion joining said upper and lower portions, inlet conduits extending downwardly through said horizontal portion, outlet conduits extending downwardly through the upper walls of said leg portions, said side walls of each leg portion having registering apertures therein, and sleeves fixed in said registering apertures and adapted to receive fasteners, whereby the lintel may be secured between the buck stays of a furnace structure.

2. A lintel for furnace structures, said lintel comprising an elongated hollow body member including forward and rear walls, a pair of hollow attaching flanges extending forwardly from said body member and having communication with the interior of said body member, said hollow flanges each having inner and outer side walls with registering apertures therein, sleeves fixed

in said registering apertures and adapted to receive fasteners, outlet means attached to each of said hollow flanges, inlet means attached to said body member, and drain conduits extending from said hollow flanges and including valve means, said rear wall of said body member including a flat vertical upper portion, a vertically inclined downwardly and rearwardly sloping lower portion, and a horizontal portion joining said upper and lower portions.
